SONIC PROTECTOR FOR EARS

John Ladd, Lynn, Mass.

Application October 31, 1955, Serial No. 543,685

3 Claims. (Cl. 2-3)

The present invention relates to a device for protecting an individual's hearing ability from injury due to excessively loud sounds.

In various industries, workers are subject to noise levels which are much in excess of the ninety decibels generally considered to be the safety maximum for human auditory senses. In many instances, the noise level exceeds 150 decibels over prolonged periods of time. At other times noise levels are suddenly increased over 150 decibels by the occurrence of explosions and the like. These excessive noise levels are, in many instances, quite harmful to workmen who are exposed to them. In many cases, particularly at higher frequency noises over prolonged periods, decibel ratings in excess of 90 decibels will cause headaches, extreme ear pains and mental fatigue.

It is an object, therefore, of the present invention to overcome these objectionable working conditions by providing an ear protecting device which is adapted to reduce the noise level considerably, while at the same time permitting normal conversation, shop noises, safety noises and other desirable sounds to be heard by the wearer of the present invention with little distortion. The present invention is not designed to eliminate completely all sounds at all frequencies. It does, however, reduce or flatten the harmful sound amplitudes to a reasonable level with the higher frequency sounds being more greatly affected than the lower frequency sounds. Speech may be clearly understood by a wearer of the present invention, although the words are slightly muffled.

It is further an object of the present invention to provide a protective device for the ear which reduces considerably the noise levels heard by the individual, but is light in weight and causes no discomfort to the wearer. The present invention also provides a structure in which no portion of the protective device is actually inserted into the ear canal, thus avoiding possible injury to the eardrum and inner ear.

A further object of the present invention is to provide a protective device for reducing noise levels heard by individuals by a percentage range of up to approximately 90%.

Further objects of the present invention provide ear protection devices which are readily adapted for use with protective helmets and which may readily be adjusted to cover the wearer's ears.

One more object of the present invention is to provide a light weight ear-protecting device which is quite comfortable to wear and which is both medically safe and easy to remove from the individual's head.

These and other objects of the present invention may be clearly understood when considered in connection with the accompanying drawings in which:

Figure 1 shows a front elevation of the invention as it is worn on the head of an individual;

Figure 2 illustrates a cross-sectional fragmentary view of the invention; and

Figure 3 illustrates a fragmentary view of a modification of the invention as used in connection with a protective helmet.

Referring specifically to the drawings of Figures 1 and 2, there is illustrated a protective device made in accordance with the present invention in which each ear is covered by a shell-like element or ear covering generally designated 1. These shell elements are open at their wide end or bottom and have a bottom opening of sufficient diameter to cover the individual wearer's ear. About the periphery of this open bottom of the shells 1 is positioned a soft yielding resilient covering or padding member generally designated 2. These sets of shell-like elements 1 are connected together by two slidable headband structures generally designated 3 and 4.

The structure of each ear covering 1 is more specifically illustrated in Figure 2. In this figure, each covering is shaped preferably in a frusto-conical form and is formed of two shell members 5 and 6, concentric with one another. Each of these conical forms are provided with outwardly extending peripheral flange elements 7 and 8 respectively at the base. The flange 8 extends beyond the flange 7 and is spaced a short distance from it. These conical members 5 and 6 are spaced apart from one another, providing an insulating air section 9. The shells are held in this spaced relation by the resilient padding (2) which is preferably formed of a foam rubber material in an elongated sleeve. One end 10 of this sleeve is secured between the shells 5 and 6 a short distance 30 down into the space 9 forming the insulation. The padding 2 extends outwardly from between the two flanges 7 and 8 where it is secured and tightly held. The other end of this annular sleeve is reversely bent in the manner as indicated. As this foam rubber should have a thickness somewhat greater than the air space 9 and the width of the flange 7, it will extend inwardly and cover a substantial portion of the flange 7. The extreme outer end of this element 2 is bent downwardly over the flange 8 onto the outside of the shell-like structure 1.

At the narrow end of this conical structure are secured the two slidable bands 3 and 4. These bands 3 and 4 are of conventional structure and may be made of elongated bands of metal, with each band 3 and 4 being divided into two overlapping sections 11 and 12. These bands 11 and 12 are held together, in longitudinal alignment for sliding upon one another to extend the elements 3 and 4 to various lengths, by the clip members 13 and 14, with clip member 13 fixed at one side to the band 11 and slidably encircling the band 12. Clip 14 is fixed securely to band 12 and slidably encircles band 11. The end of these structures 3 and 4 are secured to the shell-like member 2 by means of a bolt 15 which projects through the cones 5 and 6 and is secured in place by a nut 16. On the outside of cone 6 spacing locknuts 17 and 18 may be provided between the ends of elements 3 and 4 through which the bolt 15 passes. A gasket element 19 may also be provided on the bolt between the element 4 and the surface of the shell 6. In order to minimize the amount of noise, particularly low frequency noises passing through the shells 5 and 6, through the conduction of bolt 15, a tubular rubber-like covering 20 may be provided over the bolt 15. This tubular covering 20 is removable to allow the bolt itself to be removed.

The purpose of providing a removable nut and bolt structure 15 and 16 is to permit a ready servicing and replacement of the elements. If, however, a device is desired in which the dismountable feature of the present invention is not desired, the bolt 15 and nut 16 could be replaced by suitable rivet attaching means which would also secure the ends of the bands 3 and 4 in place.

This device as illustrated in Figures 1 and 2 is provided with a pair of bands 3 and 4 so as to permit the individual operator to adjust the protective devices over his ears in a manner individually suited to the wearer. These bands also permit a more certain gripping action of this device on the individual's head. This is quite important in many places where this device is used because the individual is subject at many times to sudden shocks and movement, such as are generated by dynamite blasts and riveting or the use of pneumatic hammers. Thus, the bands 3 and 4 may be slightly separated as in Figure 1, providing an additional gripping contact with the wearer's head.

The present invention may also be adapted for use with protective helmets, such as are used by sand hogs in the digging of underground tunnels. This modification is illustrated in Figure 3 in which 21 represents a protective helmet and 30 represents a shell member substantially similar to shell covering 1 of Figure 2. On the inner surface of this protective helmet there is provided a channel-like member 22 having essentially a U-shaped cross section with the longitudinal ends of the U attached to the sides of the helmet 21. Within this channel 22 is positioned a band 23 which terminates at its upper end in a T-shaped enlarged end 24. This band 23 is free to move up and down in the channel 22 carrying the shell covering 30 with it, but is retained from moving out of the channel the corners of this channel 22 which are peened inwardly at 25 and 26 so that the enlarged end 24 will be stopped at the ends of the channel 22. Thus, an individual wearing this protective helmet may have the helmet moved in many directions or may tilt it for individual adjustment while the protective ear covering remains in the same desired position over the ear.

Having now described my invention, I claim:

1. A device adapted to fit over and protect the human ear from loud noises comprising concentric and spaced apart inner and outer shells made of acoustically-absorbent material, outwardly-extending annular periph-

eral flanges secured to the edges of the shells with the flange on the inner shell disposed beyond and terminating radially inward from the flange of the outer shell, and an elongated annular sleeve made of resilient material extending from between the peripheries of the shells outwardly between the flanges, back over the outer surface of the flange on the inner shell and out over the outer surface of the flange on the outer shell.

2. A device of the character described comprising spaced apart and concentric frusto-conical inner and outer members made of sound insulating material and each having outwardly-extending flanges integral with their bases, said members defining an insulating air space between them, the flange of the outer member extending radially outward beyond the outer edge of the other flange, a sleeve made of sound insulating material having one end disposed between the members and extending about the outer edge of the flange of the outer member and back over the flange and to the outside of the outer member.

3. A device as defined in claim 2 further characterized by a bolt extending through the narrow ends of the members, and a sound insulating member covering the end of the bolt within the inner member and engaging the inside 25 of the inner member.
